UNITED STATES PATENT OFFICE.

SACHARY I. FEINBERG, OF NEW YORK, N. Y.

STRUCTURE OF GLASS.

No. 857,230. Filed April 28, 1905. Patented June 18, 1907.

Serial No. 257,814.

To all whom it may concern:

Be it known that I, SACHARY I. FEINBERG, a citizen of the United States, and a resident of the city, county, and State of New York, 5 borough of Manhattan, have invented a new and useful Improvement in Structures of Glass, of which the following is a specification.

The object of my invention is to provide a 10 suitable clamp for holding and securing large pieces of plate glass in their respective positions in a window or show case without recessing their edges or in any other way diminishing their strength as has been the practice heretofore. This object is accomplished by means of my invention, certain embodiments of which are hereinafter disclosed.

For a more particular description of my invention, reference is to be had to the accompanying drawings forming a part thereof, in which—

Figure 1 is a sectional and perspective view of part of a show case provided with my invention. Fig. 2 is a sectional view taken on the line 2—2 of Fig. 3, looking in the direction of the arrows. Fig. 3 is a sectional view taken on the line 3—3 of Fig. 2, looking in the direction of the arrows. Fig. 4 shows one form of clamp. Fig. 5 is a sectional view showing the clamp and plate glass. Fig. 6 shows a clamp suitable for corners and angles. Fig. 7 shows a modified detail relating to the clamp. Fig. 8 is a view similar to Fig. 1 of a further modification. Fig. 9 is a sectional view taken on the line 9—9 of Fig. 10. Fig. 10 is a sectional view showing the clamp used in Fig. 8. Fig. 11 shows the tongue and groove joint of the plates. Fig. 12 shows an angle clamp and plates, both in section. Figs. 13 and 14 each show a detached clamp.

Throughout the various views of the drawing, similar reference characters designate similar parts.

Referring to the structures shown in Figs. 1 to 6 inclusive—the window or case 1 rests on a base 2 and is formed of several plate glass panes 3, 4, 5, 6 and 7 braced by partition plates 8 and 9. The exact number of partition plates 8 and 9 depends upon the number of panes 4, 5 and 6 which number may be varied as desired. If only one is used, it is obvious that no partition plates are needed although they are preferably used at the corners as shown at 10 in Fig. 6. The plates 8

and 9 are preferably recessed at 11 to receive a part of the clamp 12. This clamp 12 comprises two parallel strips 13 and 14 united at one end by a screw 15 and at the other by a perpendicular web 16 which screw is threaded to receive a clamp screw 17 which has a cap 18 resting thereon. This cap 18 is preferably provided with a counter-sunk perforation to receive the head of the screw 17 and is given the size and outline of the web 16. The screw 15 may be provided with the ordinary head as shown in Fig. 5 which head rests in a counter-sunk hole, or it may be provided with a large knurled head 19 as shown in Fig. 4. The strips 13 and 14 may 60 be made long enough to reach the edge of the partitions 8 and 9 or may be terminated short of this and have the screw 15 pass through a perforation in the partition as shown in Fig. 5. This screw 15 may rest in a recess 20 as 70 shown in Fig. 7 or against a plate or projection 21 as shown in Fig. 3. When the clamp 12 is used at an angle or corner, as shown in Fig. 6, the web 16^a is made in a bent form, as indicated, to correspond with the 80 angle formed by the plates and the angle plate 18^a is also changed to correspond. Otherwise, the clamp 12 is unchanged. The one of the corner plates has to be slightly recessed at 28 to permit the screw 17 to join 85 the parts of the clamp together. In the corner clamp shown in Fig. 1, the strips 13 and 14 and the plate 10 are omitted.

When the window or case is assembled the plate glass panels are clamped securely by 90 the clamps 12 which are placed wherever needed and as described above.

Broadly speaking, the same idea is embodied in a different form in the structures shown in Figs. 8 to 14 inclusive. In this 95 structure the window or case 30 rests on any suitable base 31. The plate glass panes 32, 33, 34, 35 and 36 are united by partition plates 37 and 38 and clamps 39. These partition plates 37 and 38 are each formed by three layers of plates 40, 41 and 42 as shown in Figs. 9, 10, 11 and 12. The middle layer, 41 is preferably composed of a plurality of tongue and grooved plates as shown in Figs. 9 and 11, although this precise construction 105 is not necessary. The plates 38 have the middle layer 41 protrude beyond the plates 40 and 42 to form a tongue 43 which extends the thickness of the plate glass. This enables a snug fit to be formed as shown in Fig. 110.

8 between the panes 33, 34 and 35 and the plates 38, the layers 40 and 42 abutting against these panes. The plate or partition 37 is different from the plate 38 in that the 5 central layer 41 does not protrude beyond the layers 40 and 42 and these two layers are beveled to fit the angle to which the plate 37 is fitted. In this structure the panes 32 and 33 do not meet but are secured to the partition 10 37. The clamps 39 by which the partitions 37 and 38 and glass plates 32, 33, 34, 35 and 36 are secured together are similar to the clamps 12. The partition 38 is provided with recesses 44 in the tongue 43 and an adjoining recess 45 in the layers 40 and 42. In each of the recesses 44 and 45 rest a clamp 39. Each of these clamps comprise a strap 47 bent at right angles to its center 48 to form parallel strips 49 and 50 which may be 15 united at their free ends by an ordinary bolt 51. The center part 48 is provided with a screw-threaded boss 52 in which is fitted an ordinary screw 53 and on which screw is mounted the clamping cap 54 which is practically identical with the cap 18 described above. The partitions 37 are held by similar clamps 55 which are identical with the clamps 39, except that the central portions 56 are bent to fit the beveled edges of the 20 layers 40 and 42 and the cap 57 is curved to fit over the edges of the panes and span the space between their outer edges 58 and 59 as shown in Fig. 12. These clamps 55 rest in recesses 60 in the edges of the partitions 37 25 so that when the parts are in place, the glass surfaces will be in contact and form a tight joint. The parts are assembled as shown in Fig. 8 and in substantially the same manner as the parts shown in Figs. 1 and 6.

40 In the foregoing has been described certain embodiments of my invention. It is obvious that many others may be made so that I do not regard it as limited to the structures described, but as broad enough to cover all 45 structures that come within the scope of the annexed claims.

What I claim is—

1. In a device of the class described, a partition with a recessed edge, two plates abutting against the partition and a clamp resting 50

in a recess in said partition and holding said plates and partition in fixed relation.

2. In a device of the class described, a recessed partition, a clamp fixed to said partition and extending into a recess of said partition, plates abutting against said partition, a cap resting against said plates and a screw connecting said cap and that part of the clamp extending into said recess. 55

3. In a device of the class described, a partition comprised of a plurality of layers, a clamp fixed to said partition, a plurality of plates and means for uniting the clamp and plates. 60

4. In a device of the class described, a partition composed of a plurality of layers, one of said layers having members united by tongue and groove joints, a plurality of plates, and means for uniting said partition and plates. 65

5. In a device of the class described, a partition composed of a plurality of layers, a recess in the edge of said partition adapted to receive a part of a clamp, a plurality of plates, a cap, and means for uniting said clamp and cap. 75

6. In a device of the class described, a partition composed of a plurality of layers, one of said layers protruding so as to form a tongue, a plurality of plates abutting against said tongue, and means for fixedly uniting said plates and partition. 80

7. In a device of the class described, a partition composed of a plurality of layers, one of said layers protruding so as to form a tongue, a clamp fixed to said partition, a plurality of abutting plates, and means for uniting said partition and plates. 85

8. In a device of the class described, a partition composed of a plurality of plates, a recess in an edge of said partition, a clamp having a part resting in said recess, a plurality of plates, a cap and a screw connecting said clamp and cap. 90

Signed April 27th, 1905.

SACHARY I. FEINBERG.
